UNITED STATES PATENT OFFICE.

ALDUS C. HIGGINS, OF WORCESTER, MASSACHUSETTS.

ELECTRIC FURNACE.

13,027.

Specification of Reissued Letters Patent. Reissued Oct. 26, 1909.

Original No. 856,061, dated June 4, 1907, Serial No. 310,359. Application for reissue filed October 12, 1908. Serial No. 457,446.

To all whom it may concern:

Be it known that I, ALDUS C. HIGGINS, a citizen of the United States, residing at Worcester, in the county of Worcester and State of Massachusetts, have invented certain new and useful Improvements in Electric Furnaces, of which the following is a specification.

The object of the present invention is to provide an electric furnace of relatively large capacity and so constructed as to permit the product to be formed and subsequently cooled under more nearly uniform temperature conditions than has heretofore been possible, and at a rate within the control of the operator. In its preferred form the furnace is designed to facilitate the discharge or removal of the product, and the walls are effectively protected against injury due to the high internal temperature.

For a full understanding of my invention reference is made to the accompanying drawings wherein:

Figure 1 is a side elevation of one form of furnace constructed in accordance with my invention; Fig. 2 is a horizontal section on line 2—2 of Fig. 1; Fig. 3 is a central vertical section of a further modification, and Fig. 4 is a horizontal section on line 4—4 of Fig. 3.

The type of furnace shown in Figs. 1, 2, comprises a movable hearth 1 having a refractory bed or lining 2, preferably of carbon, surrounded by a metallic trough or base-ring 3 which serves to collect the water used for cooling the furnace walls or chilling the product as hereafter described. The shell or furnace casing 4 may be constructed of boiler plate or sheet-iron, and is separable from the hearth, lugs 5 being provided for lifting it therefrom. The shell is preferably inwardly inclined toward its upper end as shown. Cooling of the furnace walls, and through them of adjacent portions of the product, is effected by water supplied through perforated pipes 6 surrounding the upper portion of the shell and supported thereon by lugs 7; the perforations in pipe 6 are arranged to direct the water against the shell 4 in such manner that it flows down the inclined surface thereof in an unconfined stream or film, substantially as described in my prior patent, No. 775,654, patented November 22, 1904, to be collected by the base-ring 3 and discharged through a suitable

waste pipe 8. The furnace is shown as having stationary electrodes 9 depending into the casing in position to heat the charge or material therein either by arc or incandescence, adjacent electrodes being of opposite polarity; the crucible is adapted to be gradually lowered during the operation, as for instance by means of a direct plunger hydraulic elevator the plunger of which is shown at 10.

In electric furnace operations it is frequently desirable that overheating of the product should be avoided, and also that the product should be cooled or chilled at a definite rate within the control of the operator. As one example of an operation of this character I may mention the production of an abrasive by the fusion of an aluminum material into a pig or mass, as more fully set forth in my Patent No. 916,866, granted March 30, 1909. The character of the product in this case is dependent upon the rate at which the fused material is cooled, and it is obvious that in a furnace of large diameter the rate of cooling of a given portion of the product through external walls will depend upon the distance of such portion from the walls; and that owing to this fact the final product will vary considerably in character in accordance with such distance. In my construction such differences are minimized, and by properly proportioning the furnace in accordance with the character of the product, material which is sufficiently uniform for commercial purposes is readily obtained.

The essential feature of my construction is the production of a furnace which is of such form that while a large capacity is provided, all portions of the charge are brought within the cooling influence of cooled walls, in such manner as to secure commercial uniformity of the product. To this end I provide a relatively long and narrow furnace chamber and means for cooling the walls of the chamber. The expression "relatively long and narrow" as herein employed is not intended to indicate that the chamber must necessarily be substantially rectilinear but is intended to include annular or equivalent constructions.

Figs. 1 and 2 illustrate a furnace wherein the desired result is secured by the provision of a chamber having opposite and substantially flat water-cooled walls in such

proximity to each other as to effect a suitable cooling of the interposed charge.

Figs. 3 and 4 illustrate a further modification, comprising a cylindrical chamber 5 with water-cooled walls and depending electrodes 9—9 of opposite polarity. In order to secure in this construction the cooling of the entire body of the charge, I provide in the central portion of the furnace chamber 10 and between the electrodes, a closed water-cooled casing 10. This casing may be of sheet metal and is provided with an inlet 11 for water extending nearly to its bottom, and an outlet 12 near the top. A casing 15 of this character, like the external water-cooled walls, becomes covered in use with a solidified crust derived from the charge, and is sufficiently permanent for practical use even in operations requiring such high 20 temperatures as are necessary for the fusion of alumina. The casing is independent of the furnace structure, and may therefore be readily removed, replaced or changed without interrupting the operation. It will 25 be understood that the region between the electrodes is usually the zone of highest temperature, more particularly in the case of incandescent furnaces, and a substantially uniform temperature may be secured by abstracting heat from this region.

I claim:—

1. An electric furnace comprising a relatively long and narrow furnace chamber, a plurality of electrodes of each polarity depending into the same, and means for cool- 30

ing the furnace walls, substantially as described.

2. An electric furnace comprising a relatively long and narrow furnace chamber, the dimensions of said chamber being such as 40 to permit the effective cooling of all portions of the charge and the production of a commercially uniform product by means of a cooling medium applied to the furnace walls, a plurality of electrodes of each polarity depending into the same, and means for cooling the furnace walls, substantially as described. 45

3. An electric furnace comprising a relatively long and narrow furnace chamber, the 50 dimensions of said chamber being such as to permit the effective cooling of all portions of the charge and the production of a commercially uniform product by means of a cooling medium applied to the furnace 55 walls, electrodes of opposite polarity depending into the same, and means for cooling the furnace walls, substantially as described.

4. In combination, an electric furnace 60 having water-cooled walls, electrodes therein, and a removable water-cooled casing projecting into the charge between the electrodes, said water-cooled walls and casing coöperating to minimize the temperature 65 differences within the furnace.

ALDUS C. HIGGINS.
